UNITED STATES PATENT OFFICE

170,516

TOY VEHICLE

Morris Barry, Lakewood, N. J.

Application June 5, 1952, Serial No. 20,056

Term of patent 14 years

(Cl. D34—15)

To all whom it may concern:

Be it known that I, Morris Barry, a citizen of the United States of America, residing at city of Lakewood, county of Ocean, and State of New Jersey, have invented a new, original, and ornamental Design for a Toy Vehicle, of which the following is a specification, reference being had to the accompanying drawings, forming part thereof:

Fig. 1 is a side elevational view of a toy vehicle embodying my new design;

Fig. 2 is a top plan view thereof, the dotted line showing of the head portion of the reindeer elements having been omitted for convenience of illustration; and

Fig. 3 is an enlarged fragmentary perspective

view of that portion of the article shown to the left of Fig. 1.

The dominant features of my design are shown by means of full lines in the drawing.

I claim:

The ornamental design for a toy vehicle, as shown and described.

MORRIS BARRY.
